Primary Examiner — John Windmuller*Assistant Examiner* — Steven Czyz(74) *Attorney, Agent, or Firm* — McGuireWoods LLP(57) **CLAIM**

We claim the ornamental design for a hunting pack, as shown and described.

DESCRIPTION

FIG. 1 is a left-rear perspective view of the hunting pack;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof, shown in an alternative state and in use.

The broken lines depict portions of the article that form no part of the claimed design.
